UNITED STATES PATENT OFFICE.

JOHN DI GAUDIO, OF BROOKLYN, NEW YORK, ASSIGNOR TO MODERN LIGHTING FIXTURE CO., INC., A CORPORATION OF NEW YORK.

DESIGN FOR A LIGHTING-FIXTURE WALL BRACKET OR ARTICLE OF ANALOGOUS NATURE.

Application filed June 2, 1928. Serial No. 26,978. Term of patent 3½ years.

To all whom it may concern:

Be it known that I, JOHN DI GAUDIO, a citizen of the United States of America, and a resident of Brooklyn, county of Kings, and State of New York, have invented a new, original, and ornamental Design for a Lighting-Fixture Wall Bracket or Article or Analogous Nature, of which the following is a specification, reference being had to the accompanying drawing, forming a part hereof.

In the drawings:

Figure 1 is a front elevational view of the lighting fixture wall bracket or article of analogous nature; and

Figure 2 is a diagrammatic side outline view of the same.

I claim:

The ornamental design for a lighting fixture wall bracket or article of analogous nature, substantially as shown.

JOHN DI GAUDIO.
